GEARED AXLE DRIVE

James C. Rhoads, Erie, Pa., assignor to General
Electric Company, a corporation of New York

Application May 16, 1941, Serial No. 393,770

6 Claims. (Cl. 105—113)

My invention relates to geared railway axle drives, and particularly to an improved construction for providing an efficient geared drive and supporting structure which facilitates disconnecting the mechanical drive between the axle and the driving motor.

An object of my invention is to provide an improved geared axle drive and lubricating arrangement.

Further objects and advantages of my invention will become apparent and my invention will be better understood from the following description referring to the accompanying drawings, and the features of novelty which characterize my invention will be pointed out with particularity in the claims annexed to and forming part of this specification.

In the drawings, Fig. 1 is a plan view of a truck partly broken away and illustrates a railway axle drive embodying my invention; Fig. 2 is a side elevational view of the truck shown in Fig. 1; Fig. 3 is an enlarged partial plan view in section illustrating the improved geared axle drive shown in Figs. 1 and 2; and Fig. 4 is a sectional view illustrating an improved arrangement for removing the driving gear from the shaft of the motor shown in Fig. 3.

Referring to the drawings, I have shown a railway truck provided with side frames 10 connected together intermediate the ends thereof by a transversely extending bolster 11 provided with a center bearing plate 12 which is adapted to support the center bearing of a railway vehicle frame. The side frames 10 are formed with pedestal jaws 13 adjacent each end thereof which are arranged about journal boxes 14 and are secured together at the lower ends thereof by tie bars 15. The truck frame is resiliently supported by a plurality of coil springs 16 which engage spring seats 17 on the side frames 10 and spring seats 18 on longitudinally extending equalizers 19. The ends of the equalizers 19 are supported on the upper surfaces of the journal boxes 14 arranged about the ends of driving axles 20. These axles 20 are supported by wheels 21 and are adapted to be driven by electric motors 22 arranged one on each side of the bolster 11. The motor 22 is provided with a stationary field structure 23 which is adapted to cooperate electro-dynamically with a rotatable member 24 provided with a driving shaft 25.

Fig. 3 more clearly illustrates the gear drive, which includes a pinion spur gear 26 mounted on the motor drive shaft 25 arranged in engagement with a reduction gear 27 mounted on a counter-

shaft 28 on which a second reduction gear 29 is mounted and arranged in engagement with an axle gear 30 mounted on the driving axle 20. A gear casing is arranged about this gearing and is provided with side walls 31 and 32 having annular sleeves 33 and 34 on which sleeve bearings 35 and 36, respectively, are mounted. These bearings 35 and 36 are arranged about the axle 20 and are adapted to support an end of the gear casing thereon. A plurality of annular flanges 37 and 38 is formed on the gear casing and arranged in axially spaced apart relationship with respect to labyrinth seals 39 mounted on the axle 20 and are adapted to minimize the passage of foreign substances to the bearings 35 and 36. The opposite end of the gear casing is resiliently suspended from the bolster 11 by a link 40 which is pivotally secured by a pin 41 extending between a pair of flanges 42 formed on the gear casing. A spring 43 is arranged between a spring seat 44 on the lower end of the link 40 and on the underside of the bolster 11, so as to cushion relative vertical movements between the bolster 11 and the end of the gear casing. A second compression coil spring 43' is arranged between a spring seat washer 44' mounted adjacent the upper end of the link 40 and a flange 11' secured to the bolster 11 for supporting the adjacent end of the gear casing on the bolster as shown in Figs. 1 and 2. The countershaft 28 is supported by anti-friction roller bearings 46 and 47 mounted in removable bearing housing caps 48 and 49 secured by bolts 50 and 51 in openings formed in the sides 31 and 32, respectively, of the gear casing.

Under certain operating conditions, it becomes desirable to disconnect the mechanical connection between the axle 20 and the driving motor 22 to prevent damage to the motor or the gearing. In order to facilitate this operation, an opening 52 is formed in the side of the gear casing 32 away from the motor, and is made larger than the motor pinion gear 26 and coaxial therewith, so that this gear may readily be passed through this opening. A bearing housing cover plate 53 is removably secured by bolts 54 over the opening 52 so as to provide a closure for this opening and a bearing housing for an anti-friction roller bearing 55 which is adapted to support one end of the motor shaft 25. This bearing is provided with an outer race 56 in which the rollers 55 are mounted between a pair of radially extending flanges and the race 56 is secured within the bearing housing cap 53 between a flange 57 and a retaining plate 58 which is bolted to the bearing housing 53 by bolts 59. In this

manner, the outer bearing race 57 and the anti-friction roller bearing 55 is secured as a unit in the bearing housing cover plate 53 and is adapted to be assembled and disassembled as a unit with this cover plate. The bearing 55 is provided with an inner race 60 which is mounted on the motor shaft 25 and secured in position thereon between an axially extending threaded sleeve 61 formed on the pinion gear 26 and a retainer plate 62 secured to the end of the shaft 25 by a plurality of bolts 63. No other bearing is provided for supporting this end of the motor 25 except the bearing 55, and this construction minimizes the number of bearings and provides a more compact axle drive construction. The other end of the rotatable member 24 of the motor is supported in a bearing arranged in a bearing cap 65 mounted on the motor 22. The end of the stationary member of the motor 22 adjacent the gear casing is secured by a plurality of bolts 66 to the side 31 of the gear casing, and ventilation of the motor is provided by a fan 67 which is adapted to draw air through the motor and expel it through a plurality of openings 68 formed in the gear casing adjacent the end of the motor. An annular flange 69 is formed on the fan 67 and arranged between flanges of a labyrinth seal 70 to minimize the passage of lubricant from the gear casing along a shaft to the motor. A plurality of slinger ring flanges 71 is formed on the hub of the fan 67 so as to throw off by centrifugal force any lubricant which may pass along the shaft 25 toward the fan 67. The openings in the labyrinth seal 70 and the slinger ring flanges 71 are of larger diameter than the gear 26, thereby enabling the replacement of the driving motor, if this is required by some electrical failure, without disturbing the gear drive assembly on the vehicle axle, merely by removing the bolts 66 and horizontally moving the motor and driving gear assembly axially away from the gear casing. A new motor and driving gear may then be assembled in driving position and secured by the bolts 66 without further delay. With this construction, the gear casing is adapted to provide a lubricant reservoir for lubricating the gears of the gear reduction unit by conventional dip lubrication and lubricating the bearings which support the gear casing on the axle, the bearings which support the countershaft and the gear, and motor bearing 55 by splash lubrication of the gears in the lubricant of the gear casing.

As has been stated, under certain conditions it is desirable to break the mechanical connection between the axle 20 and the motor shaft 25, and this may readily be done in this construction by removal of the pinion driving gear 26 from the motor drive shaft 25. In order to remove the gear 26 from the shaft 25, the bearing housing cover plate 53 is unbolted from the gear casing and removed, together with the outer race 56 and the roller bearings 55. The retainer plate 62 then is unbolted from the end of the motor shaft 25, and a center bearing plug 72 is secured to the end of the shaft 25 by a screw 73. A cup-shaped gear puller 74 having an internally threaded end portion 75 then is screwed over the threaded sleeve portion 61 of the gear 26 and a bolt 76 which threadedly engages an end portion 77 of the gear puller 74 is screwed into the gear puller until the end of the bolt engages the center plug 72. The bolt 76 then is tightly drawn up and is turned until the gear 26 is loosened from its press fit on the motor shaft 25. This operation also removes the inner race 60 of the roller

bearing 55 from the shaft 25, as this inner race is made slightly smaller than the threaded sleeve 61 of the gear 26 and also slightly smaller than the inner bore 78 of the gear puller 74. After the gear 26 has been removed from the motor shaft 25, the inner sleeve 60 of the bearing may be replaced on the shaft 25 and the bearing housing cover plate 53, together with the bearing 55 may be reassembled as a unit about the inner race 66 to provide a support for this end of the rotatable member 24 of the motor. This construction provides an improved lubricating arrangement for the gears and the various bearings of the axle drive construction and an arrangement which facilitates assembly and disassembly of the motor driving pinion gear 26 for mechanically connecting and disconnecting the axle from the motor driving shaft. This construction also minimizes the number of bearings required for supporting the motor and its driving gear without necessitating the use of an overhung driving gear on the motor shaft.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States, is:

1. An axle drive including an axle with an axle gear thereon, a driving motor having a drive shaft, gearing including a gear mounted on said motor shaft for driving said axle gear, a gear casing about said gears, an opening larger than said motor shaft gear formed in a side of said gear casing away from said motor substantially coaxially with said motor shaft gear, a bearing housing cover plate removably secured to said gear casing for closing said opening, and a bearing arranged to support each end of said motor shaft, one of said bearings being arranged in said bearing housing cover plate to support an end of said motor shaft and said motor shaft gear.

2. An axle drive including an axle with an axle gear thereon, a driving motor having a drive shaft, gearing including a gear mounted on said motor shaft for driving said axle gear, a gear casing about said gears, an opening larger than said motor shaft gear formed in a side of said gear casing away from said motor substantially coaxially with said motor shaft gear, a bearing housing cover plate removably secured to said gear casing for closing said opening, and a bearing arranged to support each end of said motor shaft, one of said bearings being an anti-friction bearing for supporting an end of said motor shaft and having an inner race mounted on said motor shaft and an outer race mounted on said gear casing bearing housing cover plate, said outer race and anti-friction bearing being secured as a unit to said bearing housing cover plate and being removable therewith from said casing.

3. An axle drive including an axle with an axle gear thereon, a driving motor having a drive shaft, gearing including a gear mounted on said motor shaft for driving said axle gear, a gear casing about said gears, an opening larger than said motor shaft gear formed in a side of said gear casing away from said motor substantially coaxially with said motor shaft gear, a bearing housing cover plate removably secured to said

gear casing for closing said opening, and a bearing arranged to support each end of said motor shaft, one of said bearings being an anti-friction bearing for supporting an end of said motor shaft and having an inner race mounted on said motor shaft and an outer race mounted on said bearing housing cover plate, said outer race and anti-friction bearing being secured as a unit to said gear casing bearing housing cover plate and being removable therewith from said gear casing, said inner race being constructed and arranged for removal from said motor shaft on removal of said motor shaft gear from said motor shaft.

4. A geared axle drive including a driving motor having a drive shaft, gearing including a gear mounted on said motor shaft for driving an axle, a gear casing about said gearing, an opening in a side of said gear casing away from said motor substantially coaxial with said motor shaft gear, a bearing housing cover plate removably secured to said gear casing for closing said opening, and a bearing arranged to support each end of said motor shaft, one of said bearings being an anti-friction bearing for supporting an end of said motor shaft and having an inner race mounted on said drive shaft and an outer race mounted on said gear casing bearing housing cover plate, said outer race and anti-friction bearing being secured as a unit to said bearing housing cover plate and arranged to be removable therewith from said casing, said inner race being constructed and arranged for removal from said motor shaft on removal of said motor shaft gear from said motor shaft.

5. A gear drive including a drive shaft, a gearing including a gear mounted on said shaft, a gear casing about said gearing, an opening larger than said shaft gear formed in a side of said gear casing substantially coaxially with said shaft

5 gear, a bearing housing cover plate removably secured to said gear casing for closing said opening, and an anti-friction bearing for supporting an end of said shaft and having an inner race mounted on said drive shaft and an outer race mounted on said bearing cover plate, said outer race and anti-friction bearing being secured as a unit to said bearing housing cover plate and arranged removable therewith from said casing, means for securing a gear puller to said shaft gear, said gear puller securing means including a threaded portion larger than said inner race adapted to engage said inner race and arranged to provide for securing a gear puller to said gear over said inner race for removal of said inner race from said shaft by removal of said gear from said shaft.

6. A gear drive including a drive shaft, a gearing including a gear mounted on said shaft, a gear casing about said gearing, an opening larger than said shaft gear formed in a side of said gear casing substantially coaxially with said shaft gear, a bearing housing cover plate removably secured to said gear casing for closing said opening, and an anti-friction bearing for supporting an end of said shaft and having an inner race mounted on said drive shaft and an outer race mounted on said bearing cover plate, said outer race and anti-friction bearing being secured as a unit to said bearing housing cover plate and being removable therewith from said casing, means for securing a gear puller to said shaft gear, said inner race being constructed and arranged on said shaft to provide for securing a gear puller to said shaft without removal of said inner race and for removal from said shaft on removal of said shaft gear from said shaft.

JAMES C. RHOADS.
